UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A RANGE DOOR

Application filed July 10, 1931. Serial No. 40,493. Term of patent 14 years.

To all whom it may concern:

Be it known that I, ARTHUR STOCKSTROM, a citizen of the United States, residing in the city of St. Louis and State of Missouri, have invented a new, original, and ornamental Design for a Range Door, of which the following is a specification, reference being had therein to the accompanying drawings.

In the accompanying drawings:

Figure 1 is a perspective view of a range door having its complete face substantially

covered by the representation of tiles each tile having ornamentation on its face.

Fig. 2 is an enlarged view showing the ornamentation on the face of the tiles.

I claim:

The ornamental design for a range door substantially as shown and described.

In testimony whereof, I hereunto affix my signature.

ARTHUR STOCKSTROM.
